BROILER BURNER

Earl J. Weber, Bay Village, Ohio, assignor to American Gas Association, Incorporated, New York, N.Y., a corporation of New York

Application August 4, 1954, Serial No. 447,744

2 Claims. (Cl. 158—99)

This invention relates to broiler burners for use in domestic gas ranges.

The desirable characteristics in a domestic gas range broiler arrangement are rapid preheat and even distribution of heat over as great an area as possible. Due to the fact that the gas broiler burner is located above the broiler pan, with the flue outlet slightly above the burner level, the broiling operation depends, to a great extent on heating by radiation rather than by convection. In the conventional gas broiler arrangement, the burner is in the form of a pipe or conduit extending in a horizontal plane and having ports directed generally downward, and a mixture of fuel gas and air is supplied to the burner. The burner is configured horizontally to define a substantial area, and a relatively great number of ports are provided. The ignited fuel gas-air mixture produces rather small blue flames at the ports. In the average conventional broiler, the time required for preheating to 600° F. is about 13 minutes. The average area of the pan over which the heat is distributed is about 128 square inches. The average input rate is about 17,000 B.t.u. per hour.

The principal object of the present invention is to provide a novel gas broiler burner which is superior to the conventional broiler burner in respect to rapid preheat and even distribution of heat over a large area, and which has other advantages over the conventional burner as hereinafter set forth.

A more specific object of the invention is to provide a gas broiler burner which is of novel construction and which utilizes luminous flames to provide a high degree of radiant energy so as to achieve results heretofore unattainable.

In accordance with the invention, a gas broiler burner is provided which employs a small hollow burner head having spaced ports arranged circumferentially about the head and directed horizontally in a horizontal plane above the broiler pan. Fuel gas free of mixed air is supplied to the head, and the ignited gas burns in luminous flames extending radially from the ports. Horizontal baffle plates are provided above and below the ports, the upper plate serving to provide flame stability as well as flame carry-over on ignition, and the lower plate serving to stabilize the flames by shielding them from food vapors resulting from the broiling operation.

The invention may be fully understood from the following detailed description with reference to the accompanying drawing, wherein.

Fig. 1 is a fragmentary vertical section through the broiler compartment of a gas range, showing the gas broiler burner of the present invention in side elevation;

Fig. 2 is a substantially full-scale vertical sectional view taken centrally through the broiler burner; and

Fig. 3 is a sectional view taken along line 3—3 of Fig. 2.

Referring more particularly to the drawing, the broiler burner 10 is shown in Fig. 1 in association with the broiler pan 11 which is supported on shelf 12 within the broiler

2

compartment 13. The broiler burner 10, as best shown in Fig. 2, comprises a small hollow burner head 14 which is preferably cup-shaped as shown and which is internally threaded at its upper portion to receive the threaded end 5 of a fuel gas supply pipe 15. The burner head is also preferably cylindrical, and it is provided with equally spaced ports 16 which extend horizontally and radially through the wall of the burner head. Above the ports 16 there is a baffle plate 17 which may take the form of a relatively thick flange or disk. Below the ports 16 there is a baffle plate 18 which may take the form of a relatively large and thin disk secured to a ring 19 which surrounds and is secured to the lower end portion of the burner head. It should be noted that Fig. 2 is a full-scale illustration of a preferred embodiment, and from this it can be seen that the head 14 is quite small.

In operation, the supply pipe 15 supplies fuel gas free of mixed air to the small hollow burner head 14, and the ignited gas produces luminous flames four to five inches long which extend radially and horizontally from the ports 16. Combustion depends entirely on secondary aeration. Port velocity is maintained low enough so that the flames burn right on the ports. The velocity should be low enough so that it will not cause the flames to lift off of the ports which would result in some degree of pre-mixing of air with the fuel gas and thus reduce the luminosity of the flames. At the same time, the port velocity should be high enough to provide good secondary aeration and, hence, good combustion. The two baffles serve the purposes hereinbefore mentioned.

A gas broiler burner of the character provided by this invention not only gives very rapid preheat and a large amount of radiant heat evenly distributed over a large area, but it also has other advantages. With such a burner, there is a broad span of heats and the input rate 30 can be burned down to an extremely low value, e.g. 160 B.t.u. per hour, without extinguishing the flames. This enables the burner to serve additionally as its own pilot, eliminating the need for ignition each time the burner is used. A further advantage is that the broiling is smokeless and is evenly distributed over the surface of the food being broiled. Another advantage is that heat released to the kitchen is materially reduced.

By way of example, in the physical embodiment shown 45 full scale in Fig. 2, the burner head has an overall height of 1 1/8 inch, an outside diameter of 1 1/16 inch, an inside diameter of 7/16 inch, and a wall thickness of 1/8 inch. Spaced evenly around the circumference of the burner head are twelve No. 57 DMS ports, the angular spacing 50 between the ports being 30°. The upper baffle plate is 2 1/4 inches in diameter and has a thickness of 3/16 inch. The lower baffle plate is formed of No. 18 gauge steel and has a diameter of 4 1/16 inches. The upper baffle plate is located 1/4 inch above the port level indicated by the dot 55 and dash line, while the lower baffle plate is located 3/8 inch below the port level. This burner is rated at 14,000 B.t.u. per hour, and at this rating the heat is distributed over a broiler pan area of 174 square inches. The time for preheating to 600° F. is 10 minutes. As 60 previously stated, a conventional broiler with an input rating of about 17,000 B.t.u. per hour gives a heat distribution over an area of 128 square inches and requires about 13 minutes for preheating to 600° F. Thus, it will be seen that the present broiler burner is a substantial improvement over the conventional burner.

While a particular embodiment of the invention has been illustrated and described, the invention is not limited thereto but contemplates such modifications and further embodiments as may occur to persons skilled in the art.

I claim:

1. A broiler burner adapted to effect preheating and

even distribution of heat over a large area, comprising a hollow burner head, means to feed fuel gas under pressure and unmixed to the burner head, said burner head having no outlet openings other than spaced ports with their axes arranged circumferentially substantially in a horizontal plane through which fuel gas unmixed with air is adapted to pass whereby the ignited gas burns in spaced luminous yellow flames of substantial length extending radially from said ports, a substantially imperforate upper baffle parallel to the plane of the ports and extending laterally a sufficient distance on all sides of said burner head and above said ports to collect and hold unignited gases for enhancing flame carry-over on ignition and for stabilizing the flames, said upper baffle having a diameter at least twice as great as the diameter of said burner head, and a 15 substantially imperforate lower baffle parallel to the upper baffle and below said ports, said lower baffle extending further laterally on all sides of said burner head than said upper baffle for stabilizing the flames by shielding them from food vapors resulting from the broiling opera-

tion, the diameter of said upper baffle being approximately one-half the diameter of said lower baffle, the relative lateral dimensions and the spacing between the upper and lower baffles being selected to promote ingress of combustion air by the suction created by the burning of the gas jets whereby combustion is able to occur between the baffles and close to the ports.

2. The broiler burner of claim 1 in which the upper baffle has a diameter in the order of three times the burner head diameter and the lower baffle has a diameter in the order of six times the burner head diameter.
